GRAVEL PACKED LINER AND PERFORATION ASSEMBLY

Filed Dec. 14, 1942

FIG. 3.

FIG. 2.

FIG. 1.

John E. Eckel INVENTOR.

BY *J. G. McLean* ATTORNEY.

UNITED STATES PATENT OFFICE

2,371,385

GRAVEL-PACKED LINER AND PERFORATION ASSEMBLY

John E. Eckel, Houston, Tex., assignor to Standard Oil Development Company, a corporation of Delaware

Application December 14, 1942, Serial No. 468,921

4 Claims. (CL. 166—12)

In wells wherein the producing formation is of a sandy character it is customary to arrange a gravel pack or screen adjacent the producing formation and allow the liquid to flow from the producing formation through the gravel pack or screen into the bore of the production tubing. This arrangement substantially reduces the amount of sand carried into the well by the fluid with attendant advantages well known to the art.

The present invention is directed to a novel gravel packed screen or liner which may be lowered in position in a well without danger of contamination.

The present invention is also directed to the combination of a gravel pack liner and a bore hole gun arranged to cooperate therewith whereby weakened or thin areas in the wall of the liner may be perforated by the gun to allow the flow of fluid through the pack of granular material with which the liner is provided.

Other objects and advantages of the present invention may be seen from a reading of the following description taken with the drawing in which

Figure 1 is a view partly in section of a liner constructed in accordance with the present invention with the gravel pack sealed to prevent contamination.

Figure 2 is a view partly in section of the liner shown in Figure 1 with a bore hole gun arranged in position after firing showing the perforation of the liner, and

Figure 3 is a view partly in section of another embodiment of the liner of the present invention.

Turning now specifically to the drawing, a tubular member or liner 11 is provided at its upper end with screw threads for attachment to the lower end of a string of tubing 12. At predetermined intervals relatively large holes 13 are arranged to perforate the liner.

A relatively thin sheath 14 is arranged on member 11 and secured thereto in a fluid tight manner as by welds 15. A second sheath 16 of larger diameter than member 14 is arranged concentrically therewith with the space between the two sheaths filled with granular material 17, such as gravel or coarse sand. The upper and lower ends of the sheath 16 are preferably attached by welds 18 to the liner 11 to form a fluid tight envelope protecting granular material 17 from contamination. It will be evident that the arrangement of members 14 and 16 prevents any circulation of fluid through perforations 13, as long as they remain intact.

Below perforations 13 the interior of member 11 is arranged for engagement with a bore hole gun to guide the gun into a fixed position. In the figure the guide member is shown as a sleeve 18 with a hexagonal shaped interior. The lower end of sleeve 18 terminates in an inwardly extending ledge 19 for supporting the bore hole gun.

10 A gun perforator comprising body 21, and barrels 22 and lower end 23 suspended by a cable 24 is arranged for cooperation with the gravel packed liner above described. End 23 is given the same configuration as guide base 18 so that on lowering the gun in the screen the gun will be oriented by cooperation of member 23 with guide base 18. If the gun is lowered until cable 24 becomes slack, the weight of the gun will be supported by flange 19. Barrels 22 are spaced along the body so that each barrel will be exactly opposite a perforation 13 when lower end 23 is supported by flange 19.

15 A number of cable suspended gun perforators are well known to the art and it will be evident that any suitable firing mechanism may be used.

20 25 For example, the firing mechanism disclosed in U. S. Patent No. 2,296,318, issued September 22, 1942, may be used to control the firing of the gun.

With the arrangement of the gravel packed liner and bore hole gun above described it will be understood that the gravel pack may be placed in position and the bore hole washed without contaminating the gravel pack. After the bore hole has been cleaned thoroughly metal sheaths 14 and 16 may be perforated to allow flow of fluid from the producing zone into the bore of the well.

20 25 30 35 40 45 50 55 60 65 70 75 80 85 90 95 Granular material 17 may be any desired size and any suitable size of bullets may be projected from barrels 22. It has been found, however, that the most advantageous results are obtained by employing bullets in barrels 22 of smaller diameter than the diameter of grains 17. If the size of the granular material and bullets are proportioned in this manner, the holes produced in sheaths 14 and 16 will be smaller than the granular material 17 and hence the granular material will be retained in position after the perforation has been completed. Obviously, the size of the granular material may be selected in accordance with the present well known practices to form a pack capable of retaining the major portion of the grains of sand which may be carried into the bore of the hole by the fluid being produced. It may be stated that it is generally desirable to use a gravel pack having grains with

a mean diameter no less than .065 inch, as it is generally unsatisfactory to employ bullets in a gun perforator much smaller than $\frac{1}{8}$ of an inch in diameter. Under some conditions it may be desirable to employ a relatively soft granular material such as lumps of carbon to reduce the deflection of the bullets used in perforating the screen.

While in Figures 1 and 2 the gravel pack is shown arranged outside of the thick walled liner body 14, it will be evident that if desired, the pack may be arranged on the inside of the liner. This embodiment is illustrated in Figure 3 wherein corresponding parts are given the same numerals as in the preceding figures. In this embodiment liner 25 is not perforated but instead holes 26 are drilled only a part of the way through the liner body so that this member forms one element of the container. Sheath 27 is arranged inside the liner to form a double wall container with granular material 17 filling the space between the walls. This embodiment is arranged to be perforated by a bore hole gun in exactly the same manner as has been precedingly described. It will be understood that the embodiment shown in Figure 3 is generally less desirable than that shown in Figures 1 and 2 because there will be some tendency for the gravel pack 17 to deflect the perforating bullets and in some instances the deflected bullets may be stopped by the thick wall portion of outside liner thereby preventing a clean perforation by the bullet.

Having fully described and illustrated the preferred embodiments of the present invention, what I desire to claim is:

1. A well screen comprising in combination a relatively thick walled first tubular member having spaced weakened wall areas, a pack of granular material arranged adjacent said member, a second tubular member of relatively thin wall section arranged adjacent said first member and sealed thereto to enclose said gravel pack in a fluid tight container, and a guide means secured to said first tubular member for positioning a perforating gun having bullets arranged to be projected radially with the bullets in apposition with said spaced weakened areas.

2. A well screen comprising in combination two concentrically spaced tubular members, with

at least portions of the walls of both members of relatively thin section and in radial apposition means sealing the upper and lower ends of said members together to form a fluid tight double walled container, a pack of granular material arranged between the walls of said container, means secured to the upper end of said container for attaching it to the lower end of a string of tubing and guide means secured to said container arranged for positioning a perforating gun having bullets for radial projection with the bullets in apposition with said portions of the walls.

3. A well screen comprising, in combination, a relatively thick walled tubular member provided with a plurality of radially extending spaced perforations, a relatively thin walled tubular member arranged concentrically with said thick walled member, a second thin walled member arranged concentrically with respect to said first thin walled member and spaced therefrom, means securing the top and bottom edges of said thin walled members together to form a double walled fluid tight container, granular material arranged within said container in the form of an annular pack and means secured to said thick walled member arranged for guiding a perforating gun having bullets for radial projection to a fixed position with respect thereto with the bullets in apposition with said spaced perforations.

4. A well screen comprising in combination a relatively thick walled tubular member having a plurality of spaced wall areas from which at least a major portion of material has been removed and which are more readily traversed by radially projected bullets than the remainder of the member, a granular annulus pack arranged concentrically with respect to the tubular member, sheet means readily penetrated by bullets securing said granular pack in a fixed position with respect to said tubular member and comprising at least a portion of a container enclosing said granular pack in a fluid-tight manner and guide means secured to said tubular member arranged for guiding a perforating gun having bullets for radial projection to a fixed position at which the bullets are in apposition with said spaced portions of the tubular member.
